United States Patent Office.

HENRY KEWLEY, OF PERRY, OHIO.

Letters Patent No. 67,059, dated July 23, 1867.

IMPROVED TUBING-CLAMP.

The Schedule referred to in these Letters Patent and making part of the same.

TO ALL WHOM IT MAY CONCERN:

Be it known that I, HENRY KEWLEY, of Perry, in the county of Lake, and State of Ohio, have invented certain new and useful Improvements in Tubing-Clamps; and I do hereby declare that the following is a full and complete description of the same, reference being had to the accompanying drawings, making a part of this specification, in which—

Figure 1 is a side view of the clamps.

Figure 2 is a vertical longitudinal section.

Figure 3 is a top view.

Figure 4 is an under side view of the same.

Like letters refer to like parts in the different views.

This clamp is made of iron, and is constructed in two sections, A and B, fig. 3, which are connected to each other by the hinge-joint C, by the means of which the two sections may be opened for a purpose, as will be hereafter shown. D is a pawl, pivoted between the two sections at the point x, and is of the shape shown in fig. 2. The face of this pawl is grooved so as to conform to the circumference of the eye or hole D', into which it is seen to project, as shown in fig. 3, this being the upper part of the pawl, and the projection in fig. 4 the lower end. E is a lever inserted in the pawl, by the means of which it is operated. F is a spring, for the purpose of throwing the pawl forward into the eye. G is a bolt, by means of which the two sections are secured together. H is a brace, for the purpose of keeping the two sections apart, so as to permit a free play of the pawl. J is a boss or collar upon the under side of the clamp, the inner diameter of which is made larger than the diameter of the hole, forming thereby a recess or enlargement, J', at the lower end.

This implement is for the purpose of raising and lowering tubing into the oil-wells or other wells in which tubing is used, and is operated as follows: The clamp is placed upon the top of the curbing within the chamber, so that the implement may rest upon the shoulder K, and thereby be supported, or prevented from sliding down upon the curbing. The pipe or tube is introduced into the curbing through the eye or hole of the clamp, and as it descends into the well, the measure of its descent is controlled by the lower end of the pawl, which is forced against the tube by pulling back the lever E in the direction indicated by the dotted lines E', fig. 2, and the speed of the descending tube is thereby controlled. When it is necessary to retain the tube at any point in its descent, or to withdraw it from the well, the upper part of the pawl is thrown forward into the position shown in the drawing. By this it is obvious that its further descent is impossible so long as the pawl remains in this position, as the greater the weight downward, the stronger will be the pressure of the pawl exerted against the tube; and so, on the withdrawing of the tube from the well, the clamp is lifted up, and, as a consequence, the pipe is drawn up with it, for the descent of the tube and the lifting up of the clamp alike cause the pawl to draw tight against the pipe, in order to allow the enlargement or collar, by which the several sections of the pipe are connected, to pass through the eye. The clamp is opened by loosening the bolt, by the means of which the two sections are secured, and the clamp thereby opened sufficiently to admit of the passage of the joint, and, when passed, again closed together as before.

By the use of this clamp, tubing can be let down the well with ease and safety, and without slipping, as is the case in the old method. The more especial advantage derived from this clamp is in withdrawing the tubing from the well. In the old way of doing this with tongs, it is always attended with much labor, inconvenience, and trouble; in consequence of the slipping of the tongs, the tubing being oily, hence extremely slippery, it is very difficult to make the tongs hold sufficiently tight to withdraw the pipe. By the use of the clamp, this difficulty is avoided, for, as above remarked, the greater the weight to be lifted the stronger will be the action of the pawl against the tube, and the edge of the pawl being sharp, it cuts into the side of the tube, and thereby making it impossible for the tube to slip.

What I claim as my improvement, and desire to secure by Letters Patent, is—

The collar J, jointed sections A B, pawl D, lever E, and spring F, arranged in relation to each other in the manner and for the purpose set forth.
